UNITED STATES PATENT OFFICE

167,397

GLOVE

Roger Faré, Paris, France, assignor to Wear-Right Gloves, Inc., New York, N. Y., a corporation of New York

Application March 6, 1952, Serial No. 18,802

Term of patent 7 years

(Cl. D3—11)

To all whom it may concern:

Be it known that I, Roger Faré, a citizen of France and a resident of Paris, France, have invented a new, original, and ornamental Design for a Glove, of which the following is a specification, reference being had to the accompanying drawing, forming a part hereof in which—

Fig. 1 is a front view of a glove, showing my new design, and

Fig. 2 is a rear view thereof.

I claim:

The ornamental design for a glove, as shown.

ROGER FARÉ.
